(57) **CLAIM**

The ornamental design for a vegetation trimmer, as shown and described.

DESCRIPTION

FIG. 1 is a perspective view of a vegetation trimmer of the present invention;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The features shown in broken lines in the figures are for illustrative purposes only and form no part of the claimed design.
